UNITED STATES PATENT OFFICE.

JOHN REICHERT, OF RACINE, WISCONSIN.

TOOL FOR DEMOUNTABLE RIMS AND THE LIKE.

1,419,758.

Specification of Letters Patent. Patented June 13, 1922.

Application filed April 13, 1920. Serial No. 373,488.

To all whom it may concern:

Be it known that I, JOHN REICHERT, a citizen of the United States of America, and resident of Racine, Racine County, State 5 of Wisconsin, have invented certain new and useful Improvements in Tools for Demountable Rims and the like, of which the following is a specification.

This invention relates to certain improvements in tools for demountable rims and the like; and the objects and nature of the invention will be readily understood by those skilled in the art in the light of the following explanation of the accompanying drawings illustrating what I now believe to be the preferred mechanical expression or embodiment of my invention among other forms, constructions and arrangements within the spirit and scope thereof.

10 It is an object of my invention to provide a tool particularly adapted to be utilized for expanding and contracting demountable rims in applying the same to pneumatic or other tires, the tool being of simple and inexpensive but durable construction, and positive in its action so as to be capable of performing the work required without causing buckling of the tool, as is a common fault in tools designed for this purpose, particularly during expansion of a rim.

20

25

30

It is a further object of my invention to provide a tool of this character which is readily applied to demountable rims of various sizes, without necessitating special adjustments of the tool.

With these and other objects in view, my invention consists of certain novel features in construction, and in combinations and arrangements, as more fully and particularly set forth, and specified hereinafter.

Referring to the accompanying drawings:—

Fig. 1 is a perspective view of a demountable rim having a tire mounted thereon with my improved tool engaging the same in operative position.

Fig. 2, is a horizontal longitudinal section through my improved tool.

Fig. 3, is a transverse section through the tool taken in the plane of the line 3—3, Fig. 2.

Fig. 4 is a side elevation of the tool applied to a demountable rim and partly broken away to show the operating means.

Figs. 5 and 6 are modifications of the rim 55 gripping means at the respective ends of the tool.

My improved tool is illustrated as applied to a demountable rim A, and in the embodiment described, comprises a main frame 1, 60 having the expansion rod 2 movable longitudinally thereof, through a housing 3, the expansion rod and main frame being provided with hooks at their opposite ends adapted to engage the demountable rim at 65 diametrically opposite points, to expand or contract the latter by longitudinal movement of the expansion rod in either direction relative to the main frame.

Referring more particularly to the exemplification of the aforementioned mechanism as illustrated in Figs. 1 to 4 of the drawings, the main frame 1 is shown as an angle bar including top 1^a and side 1^b, and the expansion rod is instanced as received in the angle 75 of the main frame, which latter forms a guideway for said expansion rod.

The hooks for engaging the rim A are instanced as a single hook 4, adapted to catch over one edge of the demountable rim. This 80 hook projects beyond one end of the main frame 1, and may be secured to the top thereof as by suitable rivets, or may be formed as an integral extension 4' of the top of said main frame as illustrated in Fig. 6. 85

At the end of expansion rod 2 which is opposite the hook-end of the main frame, a pair of hooks 5, 6, are provided arranged for opening and closing movement toward and away from one another, and adapted 90 when closed to catch over the opposite side edges of the demountable rim. These hooks project beyond the end of the expansion rod, and may comprise a hook rigid with the expansion rod hook 5 for example, either suitably secured thereto as by rivets or formed as an integral extension 5' of said expansion rod as shown in Fig. 5; and an oppositely disposed hook as hook 6, pivoted to the expansion rod as at pivot 7. 95

The expansion rod 2 is adapted to be moved lengthwise of the main frame in either direction, to expand or contract the rim A engaged at opposite sides by hook 4, and hooks 5, 6, as by a rack and pinion connection between the main frame and the expansion rod. For this purpose, a rack 105 8 is provided upon the expansion rod said rack

either being cast integral with the expansion rod, or received in the channel of an expansion rod formed from suitable channel-iron. The rack preferably extends from the end of the expansion rod opposite its hook end, and may terminate short of said hook-end. It is adapted to mesh with a pinion 9, instanced as journaled in the main frame at the end thereof opposite its hook end, the top 1^a of the main frame at this point being shown as extended outwardly and provided with a bearing aperture 15 in which said pinion is journaled.

At the respective opposite faces of the pinion 9 may be provided bearing collars 11, 12, collar 11 being shown as received in the bearing aperture 15 of the main frame. Beyond collar 11 is provided a head 13 adapted to be engaged for rotating said pinion in its bearing. This head is preferably formed as a hexagonal nut to be readily grasped by a wrench, and may be also provided with a lateral aperture 14 adapted to receive a suitable lever 16 which may be formed as a tire removing tool. The above mentioned parts, including the pinion, its bearing collars and the operating head may be cast integral if found expedient.

The housing 3 is provided for the pinion 9 at its operating connection with the rack of the expansion rod, and may comprise a bottom 3^a disposed below the pinion and having a lip 17 received beneath the lower edge of side 1^b of the main frame; and side 3^b outwardly curved to fit around the pinion. The bottom 3^a is instanced as provided with a bearing aperture 18, arranged to receive the bearing collar 12 of the pinion, and said bearing collar is preferably formed with a shoulder 19 adapted to rest upon the bottom of the housing 3 for supporting the pinion 9. The ends of side 3^b of the housing beyond the outwardly curved central portion, are preferably arranged to abut against the rack of expansion rod 2, as clearly shown in Fig. 2, thereby forming a guideway for said expansion rod; and the spaces at the ends of the housing may be closed by suitable end members 3^c, fitting around the expansion rod 2 projecting beyond said housing.

The housing 3 may be properly positioned relative to the main frame 1, by suitable pins 20 projecting from the upper edge of the side of the housing arranged to be received in corresponding apertures provided in the top of the main frame. The housing when thus properly positioned, is provided with retaining means, instanced as bolts 21 received through corresponding apertures in the top of the main frame and the bottom of housing 3 respectively, the bolts being provided with suitable retaining nuts 22.

In operation, the rim to be expanded or contracted, is grasped at opposite sides, by

hook 4, and hooks 5, 6, respectively, and by rotating pinion 9 in the proper direction, the expansion rod will be moved longitudinally relative to the main frame in the direction necessary to draw the sides of the rim together, or to force them away from one another as required. When the sides of the rim have been forced into the desired position relative to one another, they may be held in such position by a locking pin 23 arranged to be inserted through either of pairs of aligned apertures 24, 25, in the top of the main frame, and the base of the housing 3 respectively, said aligned apertures being preferably arranged at opposite sides 80 of pinion 9, and so positioned that the pin 23 when inserted therein, will be received between adjacent teeth of rack 8, so as to prevent movement of the rack.

However, I do not desire to limit myself to the specific arrangement and position of the locking means as described above. Aligned apertures, such as 24, 25 can be so positioned with respect to the pinion 9, that the pin 23, when inserted therein, will be received between adjacent teeth of the pinion, to lock the pinion against rotation and prevent movement of the rack.

It is evident that various changes, modifications and variations might be resorted to without departing from the spirit and scope of my invention, and hence I do not wish to limit myself to the exact disclosure hereof.

What I claim is:—

1. A rim breaker and expander, consisting essentially of a pair of straight elongated members at their outer ends formed to abut the rim and provided with projecting hooks rigid with their respective members to rest on and catch over the rim, said members fitting one within the other and being held laterally together for relative longitudinal sliding movement on each other in opposite directions and against relative lateral movement, means whereby said members can be temporarily locked against relative longitudinal sliding movement to hold the rim expanded and contracted, and manually operated means establishing operative connection between said members for causing said relative longitudinal movement of the members to expand and contract the rim.

2. A rim breaker and expander comprising an elongated push and pull member having a longitudinal rack at its inner end portion and at its outer end formed to push the rim and provided with a hook to extend over the rim and a pivoted hook to extend under the rim, a complementary elongated push and pull member formed to push the rim and having hook means to rest on the rim, the inner end portions of said members fitting one within the other in longitudinal sliding engagement, said complementary member constructed and arranged to hold

said members laterally together in longitudinal alinement, and a gear mounted in the inner end portion of said complementary member in constant mesh with said rack and 5 freely rotatable in either direction to cause said relative longitudinal sliding movement of the members in either direction.

3. A rim breaker and expander consisting essentially of an elongated push and pull 10 member having a longitudinal rack and at its outer end formed to operatively engage the rim to push and pull the same, a complementary elongated push and pull member formed to operatively engage the rim to push 15 and pull the same, said complementary member forming a longitudinal guideway in which the inner end portion of said first named member is confined in longitudinal sliding engagement, said complementary 20 member at its inner end portion having a housing confining said members together in approximate longitudinal alinement, and a manually actuated gear carried by the inner end portion of said complementary member 25 and in constant mesh with said rack, said gear being freely rotatable in either direc-

tion to cause relative in and out longitudinal movements of said members.

4. A rim breaker and expander consisting essentially of a pair of elongated push and 30 pull members at their outer ends formed and equipped to operatively engage opposite portions of the rim to push and pull the same, the inner end portions of said members fitting one within the other in longitudinal 35 sliding engagement, said members being held in lateral engagement in approximate longitudinal alinement, one of said members having a longitudinal portion laterally projecting over the other member, gearing 40 carried by and establishing operative connection between said members for actuating the members on said relative longitudinal sliding movements, said member having said longitudinal portion being provided with a 45 pin hole aligned with a portion of said gearing and adapted to guide a removable locking pin into said gearing and hold the same in position temporarily locking said members against longitudinal movement.

JOHN REICHERT.
